UNITED STATES PATENT OFFICE.

EDWARD H. PRESBREY, OF NEW YORK, N. Y.

GREASE-CUP.

1,121,129.

Specification of Letters Patent.

Patented Dec. 15, 1914.

Application filed June 14, 1913. Serial No. 773,584.

To all whom it may concern:

Be it known that I, EDWARD H. PRESBREY, a citizen of the United States, and a resident of the city, county, and State of New York, have invented certain new and useful Improvements in Grease-Cups, of which the following is a specification.

This invention relates to grease cups in which the two members telescope together by a screw-thread, with a spring stop attached to the cup by a connection which may be fast or loose, working in connection with a pair of slots in the body, so shaped that the spring can turn only in one direction, and a thumb-screw may fasten the spring to the cup in such a way that the cup when so fastened cannot turn except in one direction, and cannot turn off; and yet a reverse motion of the thumb-screw may loosen the spring from the cap, so that the cap may turn independent of the spring, and when so loosened may be turned off. The spring and cap may turn together in screwing the cap on, to feed the grease.

The objects of my invention are 1st. To provide a positive lock, to prevent the cup from turning off from the body by the jar of the machine or otherwise, unless unlocked. 2nd. To provide means for tightening the lock with every turn of the cap or thumb-screw to feed grease. 3rd. To provide means for turning off the cap from the body by the thumb-screw when intentionally removing the cap for the purpose of charging the grease cup.

Other objects will appear from the herein-after description.

I attain these objects by the mechanism illustrated in the accompanying drawings, in which—

Figure 1 is a vertical section of my complete grease cup. Fig. 2 is a second vertical section at right angles with that of Fig. 1. Fig. 3 is a perspective view of the cap. Fig. 4 is a perspective view of the body. Fig. 5 is a perspective view of the thumb-screw. Fig. 6 is a perspective view of the split spring washer; and Fig. 7 is a perspective view of the spring; and Fig. 8 is a cross-section of Fig. 1, looking from the bottom up.

A is the cap, screw-threaded on the inside.

B is the body, screw-threaded on the outside with larger threads, C, than the remainder of the body D, so that the cup may telescope over the body the full depth of the cup.

E is the outlet, screw-threaded to enter the oil hole in the bearing to be lubricated.

F is a forked spring with a flat shoulder, f , through which is a hole, G, to receive the shank h of the thumb-screw H, having a knob M at its inner end, and the thumb-piece I outside of the cup, by which it may be turned.

The thumb-screw H is screw-threaded in the hole K, in the cup A, by left-handed threads working in corresponding threads in the hole K, and the threads C within the cup A, and on the outside of the body B are right-handed.

L is a split-spring washer between the knob M of the thumb-screw H and the flat shoulder f of the spring F. The arms of the spring F are parallel and turned in opposite directions, so that they may ride out of the grooves N in one direction.

The grooves N are on an incline when engaging the inwardly turned edge of the spring F, and have an abrupt shoulder on the opposite edge, to prevent the spring from passing the grooves in that direction while the incline aids the spring to pass the grooves in the opposite direction; and these parts are so shaped, in order that the spring when locked to the cap by the thumb-screw H will not permit the cap to be turned off, but will permit it to be screwed on.

O is the interior of the cup, intended to be charged with grease for the lubrication of a bearing.

P is the interior cavity of the body, also charged with grease, connected with the outlet E for the discharge of grease to the bearing.

The cap is preferably made smooth on the outside, so as not easily to be turned by the thumb and finger, nor turned except by the thumb-piece I.

The operation of my improved grease cup is as follows: My improved grease cup is attached by the screw-threaded outlet E to the oil hole of a bearing upon a motor, for example. Both the cap A and the body B are charged with grease and the cap screwed on to the body by a few turns of the thumb-piece I sufficient to force the grease in the body B out of the outlet E. Before the cap A is screwed upon the body D, the thumb-piece I turns the shank h of the thumb-screw H to tighten the spring F and the spring-washer L against the inside of the cup A, so that the cup A and the spring F

will turn together in screwing the cup on to the body, and the arms of the spring will ride over the grooves N and out of them, and both arms of the spring F may come to 5 rest in the grooves N. The cup A cannot turn back, and thus turn off, because the arms of the spring F on their out-turned edges engage the abrupt side of the grooves N in turning in that direction. The cap A 10 cannot be turned off by an attempt to turn the cap itself, and can only be turned off by the thumb-piece I, but when the thumb-piece I is turned in the same direction as the cap A would be turned to screw it off, the shank 15 h of the thumb-screw H is loosened in its screw threads and frees the spring F from the cap A and thumb-screw H, so that while the arms F of the spring remain in the grooves N the cap itself may be turned off, 20 but in no other way. If the thumb-screw H should happen to be left a little loose, so that the jar of the machine would tend to screw off the cap A, it would automatically screw against the knob M and thus automatically 25 tighten the spring F and the cap A together. As the spring F is in the grooves N and cannot ride out of the grooves in that direction, the jar of itself locks the cap. The thumb-piece I and screw H will not turn by 30 this jar with the cap A, because the split spring washer L, always under some tension, even when the thumb-piece I is loose, binds together the knob M and the spring F, which cannot turn in that direction out of the 35 grooves.

My improved grease cup is thus provided with means wherein an abrupt shoulder in the grooves N encounters an out-turned edge of the spring F, (Fig. 8) in such a manner that the spring F cannot ride out of the grooves N in the direction to screw off the cap A; and when the cap A, the spring F and the thumb-screw H are tight, and therefore must turn together, the cap A can- 40 not turn off. The spring F always turns in

the direction to screw the cap A on, and never can turn in the opposite direction; and it is, therefore, only when the spring F is freed from the cap A that the cap A 50 may be turned off. The cap A cannot be freed from the spring F except by turning the thumb-piece I in the direction to turn the cap A off; and by turning the thumb-piece I in that direction, it first turns a little, independent of the cap A and thus 55 loosens the spring F from the cap A, so that the cap A may turn independent of the spring. I thus realize all the foregoing objects in simple form, with few parts.

Various modifications may be made without departing from the spirit of my invention; and I have described my preferred form as an illustration, and not by way of limitation.

Having now described my invention, what 65 I claim as new and desire to secure by Letters Patent is:

1. In a grease cup, a cap and a body having an outlet, telescoping together by screw threads, in combination with a spring, 70 means to prevent the spring from rotating in a direction to screw the cap off, and for connecting and disconnecting the spring with the cap.

2. In a grease cup, a cap and a body having an outlet telescoping together by screw threads, a spring in said cap, means to prevent the spring from rotating in a direction to screw the cap off, a thumb-screw threaded 75 to tighten itself and the spring to the cap 80 when turning the cap on, and to loosen the spring from the cap when turning the cap off.

In witness whereof I have hereunto set 85 my hand, at the city, county and State of New York, this 12th day of June, 1913.

EDWARD H. PRESBREY.

In presence of—

FRANK EUFEMIA,

JOHN J. RANAGAN.
